US0D1073855S

(12) **United States Design Patent** (10) **Patent No.:** **US D1,073,855 S**
(45) **Date of Patent:** **** May 6, 2025**

(54) **DEVICE FOR CONNECTING A LURE TO FISHING LINE**

(71) Applicant: **Todd Michael Cook**, Painted Post, NY (US)

(72) Inventor: **Todd Michael Cook**, Painted Post, NY (US)

(**) Term: **15 Years**

(21) Appl. No.: **29/817,889**

(22) Filed: **Dec. 5, 2021**

(51) LOC (15) Cl. **22-05**

(52) U.S. Cl.

USPC **D22/144**

(58) **Field of Classification Search**

USPC D11/207; D22/108, 119, 121, 125, 126, D22/131, 133, 134, 143, 144, 199

CPC A01K 91/04; A01K 83/00; A01K 83/069; Y10S 24/908

See application file for complete search history.

(57) **CLAIM**

The ornamental design for a device for connecting a lure to fishing line as shown and described.

DESCRIPTION

FIG. 1 is a perspective view of the device for connecting a lure to fishing line showing my new design;

FIG. 2 is a front elevational view of FIG. 1;

FIG. 3 is a left-side elevational view of FIG. 2;

FIG. 4 is a right-side elevational view of FIG. 2;

FIG. 5 is a rear elevational view of FIG. 2;

FIG. 6 is an enlarged bottom plan view of FIG. 2;

FIG. 7 is an enlarged top plan view of FIG. 2; and,

FIG. 8 is another perspective view of FIG. 1 shown in an environmental use configuration with a lure and fishing line. The broken lines in FIGS. 1-8 depict portions of a device for connecting a lure to fishing line that form no part of the claimed design.

The additional broken lines in FIG. 8 depict environment of a device for connecting a lure to fishing line that forms no part of the claimed design.

1 Claim, 8 Drawing Sheets
